PROCESS OF PREPARING SEX HORMONES

Russell Earl Marker, State College, Pa., and
Eugene L. Wittle, Detroit, Mich., assignors to
Parke, Davis & Company, Detroit, Mich., a
corporation of Michigan

No Drawing. Application October 25, 1940,
Serial No. 362,836

27 Claims. (CL 260—397.3)

This invention relates to a process of preparing sex hormones, and more particularly, to a new and improved process for the preparation of steroid hormones from sterols and bile acids.

One object of this invention is to afford a process whereby compounds simply convertible into sex hormones can be prepared from sterols or bile acids in improved yields.

Another object of this invention is to afford a simplified process for the preparation of compounds simply convertible into sex hormones.

Yet another object of this invention is to afford a new process for the preparation of Δ^4 -3-keto steroids such as the sex hormones from Δ^4 -unsaturated sterols.

Other objects will become apparent on perusal of this specification and the appended claims.

In the past, steroid sex hormone intermediates, i. e., compounds of the androstanane and pregnane series, have been prepared by protecting the C₃ hydroxyl and the Δ^5 double bond of sterols such as cholesterol, cinchol, sitosterol and other sterols, and then oxidatively removing all or the greater portion of the side-chain attached to C₁₇. Because of the instability and sensitivity of the dihalides of esters of sterols, this process does not give very satisfactory yields. In order to obtain the best results, the conditions of oxidation must be carefully controlled and even under these conditions it is difficult to recover a reasonable amount of the unreacted starting material. On the other hand, the oxidation of sterol derivatives which are more stable than the dihalides of the esters of sterols gives better yields, but now it becomes more difficult to convert the sex hormone intermediates so formed into the sex hormones themselves. For example, while the oxidation of the acetate of coprostanol proceeds reasonably satisfactorily, the subsequent conversion of the androstanane and pregnane compounds thus obtained into sex hormones requires numerous steps with a very low overall yield.

We have set ourselves to the problem of improving the yields in the preparation of sex hormones from sterols and bile acids and to this end have succeeded in developing a process in which the step of oxidation proceeds in good yields to give intermediates which can be converted simply and in good yields to the sex hormones.

Our process consists essentially in treating a steroid of the formula,

where R is a member of the group consisting of hydrocarbon radicals and oxygenated hydrocarbon radicals, X is a halogen, and one of Y and Z is a member of the group consisting of hydrogen and halogen, the other being hydrogen, with an agent capable of oxidatively rupturing carbon-to-carbon bonds of the group R, treating the oxidation products having a shortened side-chain thus obtained to obtain the corresponding Δ^4 -unsaturated steroids, and treating these with an agent capable of oxidizing a methylene group adjacent to a double bond thus forming the corresponding 3-keto Δ^4 -unsaturated steroids having a shortened side-chain.

In greater detail, our new process consists first in forming a Δ^4 - or Δ^5 -unsaturated sterol or bile acid derivative. Because of their availability, we prefer to use as starting materials, the naturally occurring sterols in which the side-chain R is a hydrocarbon radical containing 8 to 10 carbon atoms. This side chain may be saturated, as in cholesterol C₂₈H₄₈ or sitosterol C₂₉H₅₀, or it may be unsaturated as in ergosterol C₂₉H₅₂. Sterols of this type are readily converted into the corresponding 3-desoxy compounds, i. e. into the Δ^4 or Δ^5 -unsaturated hydrocarbons. Thus cholesterol may be distilled at atmospheric pressure to give Δ^4 -cholestene, or it may be treated with phosphorous pentachloride or thionyl chloride to form cholesteryl chloride, and the latter reduced as for example with sodium and amyl alcohol to yield Δ^5 -cholestene.

The Δ^4 or Δ^5 -unsaturated steroid hydrocarbon used as a starting material is first treated with halogen or hydrohalic acid to add the elements of these substances to the steroid double bond. We prefer to use chlorine, bromine, hydrogen

chloride or hydrogen bromide in this step. The compound thus obtained has a halogen atom attached to C₈ and another halogen atom or hydrogen atom, depending upon whether halogen or hydrohalic acid was added, is attached to the other carbon atom of the original double bond.

The dihalide or hydrohalide addition product thus obtained is then oxidized under conditions sufficiently vigorous to rupture carbon-to-carbon bonds. While a variety of agents may be employed for this purpose, we prefer to use chromic acid, permanganic acid or their salts and we find it most convenient to conduct the oxidation in acetic acid below 100° C. and preferably at 35-60° C.

After the oxidation has been completed, the products are separated so as to recover any starting material and then the oxidation product consisting of a mixture of steroids having shortened, oxygenated side-chains is separated into its components according to several possible methods. It is convenient to remove the elements of halogen or hydrohalic acid at this point by treatment with a dehalogenating or dehydrohalogenating agent. Suitable dehalogenating agents include sodium iodide, zinc and acetic acid, metallic magnesium, and the like, and suitable dehydrohalogenating agents are basic substances such as pyridine, sodium acetate and other alkali metal salts of carboxylic acids, and the like.

If a Δ⁴-unsaturated steroid has been used as a starting material or if hydrogen halide was the agent added to the unsaturated steroid (either Δ⁴ or Δ⁵), then the product formed after removal of the elements of halogen or hydrohalic acid, as the case may be, is a Δ⁴-unsaturated compound. If, however, the dihalide of a Δ⁵-unsaturated steroid was the substance oxidized, after removal of the elements of halogen the product obtained is a Δ⁵-unsaturated steroid and it is necessary at some point in the process to convert this into a Δ⁴-unsaturated steroid. This is done by adding and then removing the elements of hydrohalic acid.

This shifting of the double bond from Δ⁵ to Δ⁴ in the oxidation products may be carried out at any stage after the unreacted starting material has been removed from the oxidation products but it must, of course, be done before the steroid is again oxidized to form the 3-keto steroid as set forth later in the specification.

The mixture of oxidation products is conveniently worked up by first separating the acidic and the non-acidic fractions according to methods well known in the arts. The non-acidic fraction thus obtained is further treated to isolate the ketonic fraction and from the ketonic fraction the 17-keto-androstanone compound and the 20-ketopregnane compound are isolated. Then the 17-keto androstanone compound, if it still has the double bond in the Δ⁵-position, may be converted into the corresponding Δ⁴-androstenone-17.

The Δ⁴-androstenone-17 thus obtained may be oxidized according to our new method to form Δ⁴-androstendione-3,17 and the latter selectively reduced to form Δ⁴-androstenediol-17-one-3 (testosterone). Otherwise the Δ⁴-androstenone-17 may first be selectively reduced under conditions which leave a double bond unaltered so as to form Δ⁴-androstenediol-17, the hydroxyl group of the latter protected by conversion into a derivative hydrolyzable to regenerate Δ⁴-androstenediol-17 and this derivative oxidized according to our new method to form the corresponding derivative of Δ⁴-androstenediol-17-one-3.

In either case the process involves the use of our new method for the preparation of Δ⁴-unsaturated 3-keto steroids from Δ⁴-unsaturated steroids. This method consists in oxidizing to a

5 ketone group a methylene group adjacent to a double bond and this oxidation is effected by first protecting any hydroxyl groups by converting these into derivatives such as acetates, benzoates, trityl ethers or other groups hydrolyzable to give 10 OH and oxidizing the derivative thus obtained with an agent capable of converting into a ketone group a methylene group adjacent to a double bond. Such agents include chromic acid and permanganic acid and their salts, as well as 15 selenium dioxide. The conditions of reaction depend on the particular oxidizing agent employed, e. g. we prefer to use chromic acid in acetic acid at 30-60° C.

The selective reduction of Δ⁴-androstenone-17 20 may be accomplished with a wide variety of reducing agents. These include catalytic hydrogenation with a Raney nickel catalyst, and the combination of an alkali or alkaline earth metal or aluminum and a substance having reactive 25 hydrogen atoms. Reducing agents of the latter class include such combinations as sodium and ethyl alcohol, aluminum amalgam and aqueous ammonium chloride, calcium and methanol, and the like. Instead of these the reduction may be 30 conducted according to the method of Meerwein and Ponndorf using, for example, ammonium isopropylate and isopropyl alcohol.

It will be appreciated that our invention also 35 comprehends a new group of intermediates for the preparation of sex hormones. This new group of substances is representable by the general formula

40 where Q is a member of the class consisting of (=O), groups hydrolyzable to (=O),

45 and groups hydrolyzable to

50 This group of substances includes Δ⁴-androstenone-17, its semicarbazone, its oxime, Δ⁴-androstenol-17 and its esters such as its benzoate, acetate, furoate and butyrate.

55 Our invention may be more fully illustrated by the following examples:

Example 1

(a) In a 12 liter flask is placed 230 g. of Δ⁵-cholestene dibromide prepared, e. g., according to Mauthner, Monatsch. 27, 421 (1906), and 500 cc. of carbon tetrachloride. When solution is complete, 8 liters of glacial acetic acid are added and the solution warmed to 45° C. with stirring. To this stirred solution at 48-50° C. is added dropwise a stirred solution of 320 g. of chromic anhydride in 350 cc. of water and 800 cc. of acetic acid over a period of four or five hours. The solution

is stirred at 50° C. for six hours longer and then cooled with cold water or ice to 30° C. Then ethyl alcohol (250 cc.) is added slowly to this stirred solution over a period of about one-half hour to destroy any excess chromic anhydride. The acetic acid is then removed under reduced pressure until the volume of the solution has been reduced about one-half. During the evaporation the temperature of the solution is kept at 40-45° C. The solution is cooled slightly and the unchanged dibromide filtered off and dried. The filtrate is further concentrated under reduced pressure at 40° C. until only a small quantity of acetic acid remains. This residue is diluted with 4 liters of water and 2.5 liters of ether and stirred until all the material is in solution. The water layer is separated and extracted with 2.5 liters of ether. The combined ethereal extracts are washed well with 2 liters of water, 3 liters of water containing 300 cc. of conc. hydrochloric acid, and then twice with 1.5 liters of salt water, sufficient salt being added to cause rapid separation of the layers. The ethereal solution then is evaporated to dryness, the last ether being taken off cautiously to avoid undue heat. The residue contains the dibromides of Δ^5 -androstene-17, Δ^5 -pregnenone-20, and Δ^5 -cholenic acid.

Instead of using Δ^5 -cholestene dibromide in the above step, Δ^5 -cholestene dichloride, Δ^5 -sitostene dibromide, Δ^5 -sitostene dichloride, or other dihalides of Δ^5 -unsaturated hydrocarbons derived from sterols may be used instead.

(b) One liter of acetic acid and 5 g. of zinc dust is added to this residue and the solution stirred vigorously and heated to 95° C. on the steam bath. A further 45 g. of zinc dust is added to this stirred solution in small portions over a period of forty-five minutes. Then the solution is filtered from the caked zinc and the latter washed well with acetic acid. The acetic acid filtrate is evaporated to dryness in vacuo on the steam bath and the residue dissolved in 2 liters of ether. The ethereal solution is washed twice with water and the acid fraction is extracted with 5% sodium hydroxide solution until all acids are removed.

(c) The ethereal solution is evaporated to dryness and the residue steam distilled to remove the volatile products. The residue is dissolved in ether and the water layer removed. After evaporating the ether, the residue is dissolved in 200 cc. of 95% ethyl alcohol. Five grams of semicarbazide hydrochloride and 6 g. of sodium acetate are added and the mixture refluxed on the steam bath for four hours, the alcohol being allowed to evaporate to one half volume. The solution is cooled and diluted with 500 cc. of ether. After shaking the suspension for about one-half hour with cooling, 200 cc. of water is added. The solution is shaken and cooled in a salt-ice bath and then filtered with suction. The white solid is washed well with water and ether. Then it is refluxed with 50 cc. of alcohol for one hour, cooled, filtered, and air dried; yield 5 g. of white powdered semicarbazone, M. P. 285-287° C. This is the semicarbazone of Δ^5 -androstene-17.

(d) A solution of 6.7 g. of Δ^5 -androstene-17 semicarbazone, in 500 cc. of 95% ethyl alcohol, 35 cc. of concentrated sulphuric acid and 35 cc. of water is refluxed for two and one-half hours on the steam bath. The solution is diluted with water and the organic material extracted with ether. The ethereal solution is washed well with water and sodium bicarbonate solution and evaporated to dryness. The residue is purified by distillation at 80° C. in a molecular still and crystal-

lization from dilute alcohol to yield 3 g. of Δ^5 -androstene-17, M. P. 100-105° C. On further purification the M. P. may be raised to 105-107° C.

(e) To a solution of 1.7 g. of Δ^5 -androstene-17 in 26 cc. of refluxing n-propyl alcohol is added 2.5 g. of sodium in small portions over a period of a half hour. Then the solution is poured into water and the white solid collected. This is crystallized from methanol to yield 1.4 g. of Δ^5 -androstenol-17, M. P. 163-165° C.

Three grams of Δ^5 -androstenol-17 is refluxed for one hour with 30 cc. acetic anhydride and then the solution is evaporated to dryness under reduced pressure. The residue is dissolved in hot methanol and allowed to crystallize. The Δ^5 -androstenol-17-acetate thus formed has M. P. 133-135° C. Hydrolysis of this acetate, e. g., with alcoholic potassium hydroxide, regenerates the original hydroxy compound, Δ^5 -androstenol-17.

(f) A stream of dry hydrogen chloride is bubbled for several hours through a solution of 1 g. of Δ^5 -androstenol-17 in about 20 cc. of chloroform, cooled to 0° C. After the cold solution has stood for several hours, it is carefully evaporated to dryness under reduced pressure on a water bath. The white solid hydrochloride remaining behind is dissolved in ethyl alcohol and refluxed for six hours with 4 g. of fused potassium acetate. The resulting solution is poured into water and the precipitate collected and dried. This crude product is acetylated by refluxing it with acetic anhydride for two hours. Fractional crystallization of the acetylated product yields a small amount of the less soluble Δ^5 -androstenol-17 acetate M. P. 133-135° C., and a larger amount of the more soluble Δ^4 -androstenol-17 acetate M. P. 97-100° C. A mixture of these two acetates gives a depression in melting point to 72-82° C.

A solution of 500 mg. of Δ^4 -androstenol-17 acetate, M. P. 97-100° C. in 25 cc. of methanol is refluxed for a half hour with a solution of 1 g. of potassium hydroxide in 10 cc. of 50% methanol. The solution is diluted with water and extracted with ether. The ethereal solution is washed with water and evaporated to dryness. The Δ^4 -androstenol-17 is purified by crystallization from methanol, and then has M. P. 146-149° C.

To a solution of 200 mg. of Δ^4 -androstenol-17 in 100 cc. of acetic acid is added 0.73 cc. of 1.05 molar bromine in acetic acid. After a few minutes, a solution of 300 mg. of chromic anhydride in 20 cc. of 90% acetic acid is added with shaking. The solution is allowed to stand at room temperature for one hour and then warmed with five grams of zinc dust on the steam bath. The solution is filtered, poured into water and the product extracted with ether. The ethereal solution is washed well with water and dilute alkali and evaporated to dryness. The residue is distilled in a molecular still under reduced pressure and then crystallized from dilute methanol to give Δ^4 -androstene-17 of M. P. 78-80° C. This ketone gives a depression in melting point to 60-65° C. when mixed with Δ^5 -androstene-17.

(g) To a solution of 2 g. of Δ^4 -androstenol-17 acetate in 75 cc. of glacial acetic at 50° C. is added a solution of 2 g. of chromic anhydride in 25 cc. of 90% acetic acid over a period of one hour. The solution is poured into water and extracted with ether. The ethereal solution is washed well with water and dilute sodium carbonate solution and then evaporated to dryness. The resulting oil, which shows a high androgenic activity, is treated in the known manner with Girard's reagent T to separate the ketonic fraction. The

crude ketone is hydrolyzed by warming with alcoholic hydrochloric acid and then distilled in a molecular still at 0.01 mm. pressure. Crystallization of the product so obtained from ether-pentane or dilute methanol gives testosterone, M. P. 148-150° C., identical with the natural product.

Example 2

(a) Δ^4 -Androstenol-17 is prepared, e. g., as described in Example 1 (f).

(b) To a solution of 2.5 g. of Δ^4 -androstenol-17 in 200 cc. of acetic acid is added at 35-45° C. and with stirring, a solution of 3 g. of chromic anhydride in 50 cc. of 90% acetic acid. The addition requires one-half hour and the solution is then kept at 45° C. for another half hour. The solution is poured into water and extracted with ether. The ethereal layer is washed well with sodium carbonate solution and water and concentrated to a small volume. On cooling this solution for some time crystals form and are collected. They may be recrystallized from ether to yield Δ^4 -androstenedione-3,17, M. P. 168-170° C., identical with the known substance.

Example 3

(a) Δ^5 -Cholestene, prepared, e. g., by the reduction of cholesteryl chloride with sodium and alcohol, is converted into 5-chlorocholestane by adding hydrogen chloride as described by Mauthner, *Monatsh.* 28, 1113 (1907).

(b) Two hundred grams of 5-chlorocholestane in 500 cc. of carbon tetrachloride and 4 l. of acetic acid are stirred and maintained at 50° C. while a solution of 150 g. of calcium permanganate in 600 cc. of water, 100 cc. of sulfuric acid, and 2 l. of acetic acid is added over a period of four hours. The mixture is stirred four hours more at 50° C., and then sulfur dioxide passed into the solution with cooling. The mixture is concentrated to one-third its former volume in vacuo, 700 g. of sodium acetate added, and the mixture refluxed for two hours. It is diluted with water and well extracted with ether. The ethereal layer is shaken with 10% sodium hydroxide and the sparingly soluble sodium salt which forms is removed by filtration. The filtrate, consisting of an ethereal and an aqueous phase, is set aside for later treatment as described under (d) below.

(c) The sparingly soluble sodium salt is suspended in water, and the suspension acidified strongly. This mixture is well extracted with ether and the latter washed and evaporated. The residue is crystallized from slightly diluted acetic acid and thus yields Δ^4 -cholenic acid of M. P. 160° C.

(d) The ethereal layer in the filtrate is separated and washed well with sodium hydroxide solution and water. After removing the ether on a steam bath, the residue is heated with 200 cc. of acetone, some methanol added, and the mixture chilled. The crude Δ^4 -cholestene which separates is collected and recrystallized. The combined mother liquors are evaporated to dryness, and the ketonic constituents removed in the known manner with Girard's reagent T. The crude ketone mixture is distilled slowly in a high vacuum and a fraction collected at 70-110° C. This is fractionally crystallized from dilute methanol and thus yields. Δ^4 -androstenone-17 of M. P. 78-80° C.

(e) The combined mother liquors from the above described crystallization of Δ^4 -androstenone-17 contains Δ^4 -androstenone-17 and Δ^4 -pregnenone-20, and are evaporated to dryness

and dissolved in 50 cc. of acetic acid. To this solution, at 45° C., there is added a solution of 1.5 g. of chromic anhydride in 20 cc. of 90% acetic acid over a period of a half hour. The mixture is poured into water, extracted with ether, and the ethereal extract washed with sodium hydroxide solution and water. The ethereal solution is dried over magnesium sulfate, evaporated to a small volume, and rendered cloudy by the addition of ligroin. On standing, crystals of Δ^4 -androstenedione-3,17 separate. After recrystallization, this product melts at 170°. The mother liquor from the separation of the Δ^4 -androstenedione-3,17 is made slightly turbid with ligroin and filtered through a column of alumina. The filtrate is evaporated and yields, after crystallization from dilute acetone, progesterone of M. P. 122° C.

Example 4

(a) Δ^4 -Cholestene is prepared by distilling cholesterol at atmospheric pressure according to the method of Heilbron and Sexton, *J. Chem. Soc.* 1928, 347.

(b) To 100 g. of Δ^4 -cholestene in 500 cc. of carbon tetrachloride is added a 30% solution of bromine in carbon tetrachloride until the double bond is saturated with bromine. Then the mixture is warmed to 50° C., 2 l. of acetic acid added, and a solution of 100 g. of chromic anhydride in 1 liter of 90% acetic acid at 50° C. over a period of four hours. After stirring for four hours more at this temperature, 150 g. of zinc dust is added, in small portions, and the mixture allowed to stand overnight. The next day the solution is decanted from the sludge, and concentrated in vacuo. The residue is dissolved in water and ether, the layers separated, and the ethereal layer washed with sodium hydroxide solution. The ethereal extract is then evaporated to dryness, and the ketones removed from the residue in the known manner as the semi-carbazones. After hydrolysis of the purified semicarbazone, Δ^4 -androstenone-17 of M. P. 79° C. is obtained.

(c) To 1.5 g. of Δ^4 -androstenone-17 in 100 cc. of acetic acid at 40° C. there is added slowly over a period of an hour, a solution of 1.5 g. of potassium permanganate in 20 cc. of water and 50 cc. of acetic acid. After standing for an additional hour, the mixture is saturated with sulfur dioxide, concentrated to a small volume, and diluted with water. This mixture is extracted with ether and the ethereal layer washed with alkali and water and evaporated to dryness. The residue yields, after crystallization from ether-pentane, Δ^4 -androstenedione-3,17 of M. P. 168-70° C.

Example 5

(a) Δ^4 -Pregnenone-20, M. P. 105° C., may be isolated from the mother liquors of the preparation of Δ^4 -androstenone-17 as in Example 3, (d), or it may be prepared from Δ^5 -pregnenol-3(β)-one-20 by the steps of treatment with phosphorus pentachloride to obtain Δ^5 -3-chloropregnenone-20, treating this with sodium and amyl alcohol to obtain Δ^5 -pregnenol-20(α), and treating this as in Example 1, to obtain Δ^4 -pregnenone-20.

(b) To a solution of 2 g. of Δ^4 -pregnenone-20 in 30 cc. of acetic acid at 45° C. is added over a period of an hour, a solution of 2 g. of chromic anhydride in 50 cc. of acetic acid. After standing two hours, sulfur dioxide is passed into the solution to destroy the excess chromic anhydride, and then the mixture is evaporated in vacuo.

The residual syrup is dissolved in ether, shaken out with 5% sodium hydroxide and water, and the ethereal extract evaporated. The residue is sublimed in a high vacuum and then crystallized from dilute acetone and thus gives progesterone melting at 120° C.

The above examples are intended to illustrate but not to limit the scope of our invention. Other modes of employing our process apparent to those skilled in the art after this disclosure, are intended to fall within the scope of our invention and accordingly we wish to limit the scope of our invention only as indicated in the appended claims.

What we claim as or invention is:

1. The process which comprises treating a steroid of the formula,

where R is a member of the group consisting of hydrocarbon radicals and oxygenated hydrocarbon radicals, X is a halogen, and one of Y and Z is a member of the group consisting of hydrogen and halogen, the other being hydrogen, with an agent capable of oxidatively rupturing carbon-to-carbon bonds, treating the oxidation products having a shortened side-chain thus obtained to obtain the corresponding Δ^4 -unsaturated steroids, said treatment being determined by the nature of Y and Z, so that when Y is halogen and Z is hydrogen, the treatment comprises the step of reacting the oxidation products with a dehalogenating agent, when Y and Z are both hydrogen the treatment comprises the step of reacting the oxidation products with a dehydrohalogenating agent, and when Y is hydrogen and Z is halogen the treatment comprises the steps of reacting the oxidation products successively with a dehalogenating agent, a hydrogen halide, and a dehydrohalogenating agent, and subjecting said Δ^4 -unsaturated steroids to the action of an oxidizing agent capable of oxidizing to a ketone group a methylene group adjacent to a double bond, said oxidizing agent being selected from the group consisting of compounds of hexavalent chromium, compounds of heptavalent manganese, and selenium dioxide, thus forming the corresponding 3-keto Δ^4 -unsaturated steroids having a shortened side-chain.

2. The process which comprises treating a steroid of the formula,

where R' represents a sterol-side chain containing 8 to 10 carbon atoms, and X is selected from the class consisting of chlorine and bromine with an oxidizing agent selected from the class consisting of chromic acid, permanganic acid, and

their salts, treating the oxidation products thus obtained with a dehalogenating agent, isolating the Δ^5 -androstenone-17 thus formed, converting said Δ^5 -androstenone-17 into Δ^4 -androstenone-17 by addition and subsequent removal of hydrohalic acid, reducing to a carbinol group the ketone group of said Δ^4 -androstenone-17 under conditions which leave double bonds unaltered, protecting the C17 hydroxyl group by conversion into a derivative hydrolyzable to regenerate the C17 hydroxyl group, treating said derivative of Δ^4 -androstenol-17 with an oxidizing agent capable of oxidizing to a ketone group a methylene group adjacent to a double bond, said oxidizing agent being selected from the group consisting of compounds of hexavalent chromium, compounds of heptavalent manganese, and selenium dioxide, and separating the 3-keto- Δ^4 -androstenol-17 compound thus produced.

3. The process which comprises treating a steroid of the formula,

where R' represents a sterol-side chain containing 8 to 10 carbon atoms, and X is selected from the class consisting of chlorine and bromine with an oxidizing agent selected from the class consisting of chromic acid, permanganic acid, and their salts, treating the oxidation products thus obtained with a dehalogenating agent, isolating the Δ^4 -androstenone-17 thus formed, reducing to a carbinol group the ketone group of said Δ^4 -androstenone-17 under conditions which leave double bonds unaltered, protecting the C17 hydroxyl group by conversion into a derivative hydrolyzable to regenerate the C17 hydroxyl group, treating said derivative of Δ^4 -androstenol-17 with an oxidizing agent capable of oxidizing to a ketone group a methylene group adjacent to a double bond, said oxidizing agent being selected from the group consisting of compounds of hexavalent chromium, compounds of heptavalent manganese, and selenium dioxide, and separating the 3-keto- Δ^4 -androstenol-17 compound thus produced.

4. The process which comprises treating a steroid of the formula,

where R' represents a sterol-side chain containing 8 to 10 carbon atoms, and X is selected from the class consisting of chlorine and bromine with an oxidizing agent selected from the class consisting of chromic acid, permanganic acid, and their salts, treating the oxidation products thus obtained with a dehydrohalogenating agent, isolating the Δ^4 -androstenone-17 thus formed, reducing to a carbinol group the ketone group of said Δ^4 -androstenone-17 under conditions which leave

double bonds unaltered, protecting the C₁₇ hydroxyl group by conversion into a derivative hydrolyzable to regenerate the C₁₇ hydroxyl group, treating said derivative of Δ^4 -androstenedol-17 with an oxidizing agent capable of oxidizing to a ketone group a methylene group adjacent to a double bond, said oxidizing agent being selected from the group consisting of compounds of hexavalent chromium, compounds of heptavalent manganese, and selenium dioxide, and separating the 3-keto- Δ^4 -androstenedol-17 compound thus produced.

5. The process which comprises treating a steroid of the formula,

where R' represents a sterol-side chain containing 8 to 10 carbon atoms, and X is selected from the class consisting of chlorine and bromine with an oxidizing agent selected from the class consisting of chromic acid, permanganic acid and their salts, treating the oxidation products thus obtained with a dehalogenating agent, isolating the Δ^5 -androstenedone-17 thus formed, reducing to a carbinol group the ketone group of said Δ^5 -androstenedone-17 under conditions which leave double bonds unaltered, converting said Δ^5 -androstenedol-17 into Δ^4 -androstenedol-17 by addition and subsequent removal of hydrohalic acid, protecting the C₁₇ hydroxyl group by conversion into a derivative hydrolyzable to regenerate the C₁₇ hydroxyl group, treating said derivative of Δ^4 -androstenedol-17 with an oxidizing agent capable of oxidizing to a ketone group a methylene group adjacent to a double bond, said oxidizing agent being selected from the group consisting of compounds of hexavalent chromium, compounds of heptavalent manganese, and selenium dioxide, and separating the 3-keto- Δ^4 -androstenedol-17 compound thus produced.

6. The process which comprises treating 5,6-dibromocholestane with an excess of chromic acid in acetic acid at 35-60° C., treating the oxidation products thus obtained with zinc dust, isolating the Δ^5 -androstenedone-17 thus formed, reducing to a carbinol group the ketone group of said Δ^5 -androstenedone-17 with a reducing agent selected from the class consisting of, (a) metals more electropositive than zinc in combination with a substance having reactive hydrogen atoms, (b) molecular hydrogen and a nickel catalyst, and (c) the combination of an aluminum alcoholate and a secondary alcohol, converting the Δ^5 -androstenedol-17 thus formed into Δ^4 -androstenedol-17 by addition and subsequent removal of an agent selected from the class consisting of hydrogen chloride and hydrogen bromide, acylating the C₁₇ hydroxyl group to form 17-acyloxy- Δ^4 -androstene, treating said 17-acyloxy- Δ^4 -androstene with chromic acid in acetic acid at 30-60° C. and separating the 17-acyloxy- Δ^4 -androstenedone-3 thus produced.

7. The process which comprises treating 5-chloro cholestane with an excess of chromic acid in acetic acid at 35-60° C., treating the oxidation

products thus obtained with an alkali metal salt of an organic acid, isolating the Δ^4 -androstenedone-17 thus formed, reducing to a carbinol group the ketone group of said Δ^4 -androstenedone-17 with a reducing agent selected from the class consisting of, (a) metals more electropositive than zinc in combination with a substance having reactive hydrogen atoms, (b) molecular hydrogen and a nickel catalyst, and (c) the combination of an aluminum alcoholate and a secondary alcohol, acylating the C₁₇ hydroxyl group of the Δ^4 -androstenedol-17 thus formed, treating said 17-acyloxy- Δ^4 -androstene with chromic acid in acetic acid at 30-60° C. and separating the 17-acyloxy- Δ^4 -androstenedone-3 thus produced.

8. The step which comprises reducing Δ^4 -androstenedone-17 with a reagent selected from the class consisting of, (a) metals more electropositive than zinc in combination with a substance having reactive hydrogen atoms, (b) molecular hydrogen and a nickel catalyst, and (c) the combination of an aluminum alcoholate and a secondary alcohol, to form Δ^4 -androstenedol-17.

9. The step which comprises treating an ester of Δ^4 -androstenedol-17 with chromic acid in acetic acid at 30-60° C., thus forming an ester of Δ^4 -androstenedol-17-one-3.

10. Δ^4 -Androstenedol-17-acetate of melting point approximately 97-100° C.

11. An ester of the formula

where R' is the acyl radical of a lower aliphatic carboxylic acid.

12. The process which comprises subjecting a steroid of the formula,

55 where R' is a sterol-side chain containing 8 to 10 carbon atoms and X is selected from the class consisting of chlorine and bromine, to oxidative side chain degradation by treatment with an oxidizing agent selected from the class consisting of chromic acid, permanganic acid, and their salts, treating the oxidation products thus obtained with a dehalogenating agent, converting the Δ^5 -unsaturated ketonic steroids thus obtained into the corresponding Δ^4 -unsaturated steroids by addition thereto and subsequent removal therefrom of hydrohalic acid, and oxidizing said Δ^4 -unsaturated steroids with an oxidizing agent capable of oxidizing to a ketone group a methylene group adjacent to a double bond, said oxidizing agent being selected from the group consisting of compounds of hexavalent chromium, compounds of heptavalent manganese and selenium dioxide, thereby obtaining at least one member of the class consisting of Δ^4 -androstenedione-3,17 and

70 Δ^4 -pregnenedione-3,20.

13. The process which comprises subjecting a steroid of the formula,

where R' is a sterol-side chain containing 8 to 10 carbon atoms and X is selected from the class consisting of chlorine and bromine to oxidative side chain degradation by treatment with an oxidizing agent selected from the class consisting of chromic acid, permanganic acid, and their salts, treating the oxidation products thus obtained with a dehalogenating agent, and oxidizing the resulting Δ^4 -unsaturated ketonic steroids with an oxidizing agent capable of oxidizing to a ketone group a methylene group adjacent to a double bond, said oxidizing agent being selected from the group consisting of compounds of hexavalent chromium, compounds of heptavalent manganese, and selenium dioxide, thereby obtaining at least one member of the class consisting of Δ^4 -androstenedione-3,17 and Δ^4 -pregnenedione-3,20.

14. The process which comprises subjecting a steroid of the formula,

where R' is a sterol-side chain containing 8 to 10 carbon atoms and X is selected from the class consisting of chlorine and bromine, to oxidative side chain degradation by treatment with an oxidizing agent selected from the class consisting of chromic acid, permanganic acid, and their salts, treating the oxidation products thus obtained with a dehydrohalogenating agent, and oxidizing the resulting Δ^4 -unsaturated ketonic steroids with an oxidizing agent capable of oxidizing to a ketone group a methylene group adjacent to a double bond, said oxidizing agent being selected from the group consisting of compounds of hexavalent chromium, compounds of heptavalent manganese, and selenium dioxide, thereby obtaining at least one member of the class consisting of Δ^4 -androstenedione-3,17, and Δ^4 -pregnenedione-3,20.

15. The process which comprises oxidizing 5,6-dibromocholestane with an excess of chromic acid in acetic acid at 35-60° C., dehalogenating with zinc dust the oxidation products thus obtained, converting the resulting Δ^5 -unsaturated ketonic steroids to the corresponding Δ^4 -unsaturated steroids by addition thereto and subsequent removal therefrom of an agent selected from the class consisting of hydrogen chloride and hydrogen bromide, and oxidizing said Δ^4 -unsaturated steroids with chromic acid in acetic acid at 30-60° C., thereby obtaining at least one member of the class consisting of Δ^4 -androstenedione-3,17 and Δ^4 -pregnenedione-3,20.

16. The process which comprises oxidizing 5-chlorocholestane with an excess of chromic acid in acetic acid at 35-60° C., dehydrohalogenating the ketonic steroids thus obtained with an alkali metal salt of an organic acid, and oxidizing the resulting Δ^4 -unsaturated ketonic steroids with chromic acid in acetic acid at 30-60° C., thereby obtaining at least one member of the class consisting of Δ^4 -androstenedione-3,17 and Δ^4 -pregnenedione-3,20.

17. Δ^4 -Androstene-17-ol acylates.

18. Δ^4 -Androstene-17-ol.

19. A process of the character described which comprises treating an androstan-17-one, containing only a double bond in the rings A and B, with an agent capable of transforming the group —CO— into the group —CH(OH)— , then with an esterifying agent, and then causing the product thus obtained to react with an oxidizing agent capable of introducing a keto group into the α -position of double bonds.

20. The dimethyl cyclopantanopolyhydrophenanthrene compounds containing in the 17-position an oxo-group and in the rings A and B only a carbon double bond.

21. The dimethyl cyclopantanopolyhydrophenanthrene compounds containing in the 17-position an oxo-group and in the rings A and B only a carbon double bond in 4:5-position.

22. The Δ^4 -androstene-17-one of the formula:

23. The step which comprises treating a steroid of the formula

where Q is a member of the class consisting of (=O) ,

with an oxidizing agent capable of oxidizing to a ketone group a methylene group adjacent to a double bond, said oxidizing agent being selected from the group consisting of compounds of hexavalent chromium, compounds of heptavalent manganese, and selenium dioxide, thus forming a 3-keto- Δ^4 -unsaturated steroid.

24. The step which comprises treating a steroid of the formula

where Q is a member of the class consisting of
(=O),

with chromic acid in acetic acid at 30-60° C., thus forming a Δ^4 -unsaturated steroid.

25. The process which comprises treating Δ^4 -androstenedione-17 with an oxidizing agent capable of oxidizing to a ketone group a methylene group adjacent to a double bond, said oxidizing agent being selected from the group consisting of compounds of hexavalent chromium, compounds of heptavalent manganese, and selenium dioxide, thus forming Δ^4 -androstenedione-3,17. 10

26. The process which comprises treating Δ^4 -androstenedione-17 with chromic acid in acetic acid at 30-60° C., thus forming Δ^4 -androstenedione-3,17. 15

27. A compound of the formula

where Q is a member of the class consisting of
(=O),

RUSSELL EARL MARKER.
